UNITED STATES PATENT OFFICE.

GEORGE WAGENLANDER, OF WASHINGTON, DISTRICT OF COLUMBIA.

INTERNAL-COMBUSTION ENGINE.

Application filed September 21, 1922. Serial No. 589,581.

To all whom it may concern:

Be it known that I, GEORGE WAGENLANDER, a citizen of the United States, residing at Washington, District of Columbia, have invented certain new and useful Improvements in Internal-Combustion Engines, of which the following is a specification.

This invention relates to internal combustion engines of the oscillating piston type in which the oscillation of one or more pistons is communicated primarily to a rock shaft by direct connection therewith, and from the rock shaft is communicated by a crank and connecting rod to a crank shaft rotating in one direction.

The object of the invention is to provide an improved construction of the type stated.

A further object of the invention is to improve the valve mechanism for an engine of this kind, the valves being of the sliding plate type, and the arrangement is such that a multiplicity of cylinders can be controlled by the same valve gearing.

Improved details will be apparent in the construction and arrangement of the cylinders, pistons and connecting mechanism, designed to provide a fully balanced engine which will run without excessive vibration, and which by the multiplication of cylinders may provide a practically continuous power impulse communicated to the crank shaft.

Further features of improvement relate to the ease and convenience with which the parts may be assembled, and with which the valve movement can be adjusted to compensate for wear or otherwise.

The invention may be realized in an engine containing one or more cylinders. Preferably multiple cylinders will be employed, and for the purpose of illustration I have shown a four cylinder engine.

Various other advantages of construction and operation will be apparent from the following description and the accompanying drawings in which Fig. 1 is a side elevation of the engine. Fig. 2 is a top plan view thereof. Fig. 3 is a vertical section on the line 3—3 of Fig. 4. Fig. 4 is a vertical section on the line 4—4 of Fig. 3. Fig. 5 is an end elevation of what will be termed the front end of the engine. Fig. 6 is a similar elevation with the front plate removed. Fig. 7 is a top plan view with the cylinder head removed. Fig. 8 is a bottom plan view of the cylinder head. Fig. 9 is a top plan in detail of the timing gears and a portion of

the crank shaft. Fig. 10 is a front elevation of the cam and valve shaft. Fig. 11 is a detail of the pistons. Fig. 12 is a lay-out of one of the cams. Fig. 13 is a plan view of piston packing. Fig. 14 is a similar view of other parts of the packing. Fig. 15 is a section of the valve shaft. Fig. 16 is a detail in section showing the valve packing.

The engine illustrated is of the four cycle type, and the construction and operation will be described with reference to an engine of that type.

The cylinder block is indicated as a whole at 6 and may be mounted on any suitable base 7. In this block four cylinders 8 are produced, and these cylinders are segmental in shape and are arranged in two pairs the units of which are located at opposite sides of a common center, and the lower part of the cylinder block, in connection with the base, forms a crank case in which splash lubrication may be employed. The cylinders are square in cross section, this form being preferred to a circular section, altho the latter may be employed if desired, and the block is closed at the front end by a front plate 9 bolted to the cylinder block, and at the other end by a rear plate 10 bolted thereto, these plates forming the outer walls of the cylinders.

Located at the center of the block, or rather at the common center of the cylinders, is a rock shaft 11 which is supported by bearing webs 12 cast in the block. The lower half of the bearings, indicated at 12^a, is preferably made removable, so that the rock shaft can be removed or the bearing adjusted from below. That is the bearing caps are on the under side. The rock shaft extends from front to rear horizontally of the block, but need not extend through the end plates. At its front end the shaft has a counterbalanced crank 13 which is connected by a rod 14 to a crank 15 on the end of the crank shaft 16 which is carried in bearings 17 at the base of the block, and the rear end of this crank shaft extends through the rear plate 10. The front plate is bossed or recessed as indicated at 9^a to give room for the cranks and connecting rod. The cranks 13 and 15 are so proportioned that oscillation of the former will produce continuous rotation of the latter, whereby a single direction of movement is imparted to the latter.

Each pair of pistons consists of a single substantially semi-circular rod 18, at each

end of which is a piston head which work in the corresponding opposite cylinders. This casting as most clearly shown in Fig. 4 has the shape of a channel in cross section, and 5 the two castings are bolted to opposite sides of a rocker 19 which is keyed on the rock shaft 11 as shown at 20 and provided with a counterbalance 21, the counterbalance being located on the opposite side of the axis 10 to the piston connection, and of a mass sufficient to substantially balance the weight of the pistons. In the four cylinder construction shown this rocker is conveniently located at the middle of the rock shaft, between 15 its bearings, and the bolts by which it is connected to the pistons are shown at 22.

Each piston head comprises a square web 23 (Fig. 11) with a bolt 24 connecting the same to a square face plate 25 of the same 20 diameter as the piston, with a spacing sleeve 26 set between the web and the face plate. The packing sections shown in Figs. 13 and 14 are set in this space. That shown in Fig. 13 consists of four triangular pieces 40 set 25 to form a square with a spring ring 42 tending to expand the same, and under these are two sets of sections shown in Fig. 14, each section consisting of two pieces 41 shaped to form a square, and set so that the joints 30 between the sections of one will be broken by the solid part of the other, thus insuring a tight piston head.

From the construction thus far described it will be seen that reciprocation of the 35 piston heads in the segmental cylinders will transmit an oscillatory movement to the rocker and rock shaft, and rotation to the crank shaft. The spark plugs 43 may be conveniently set in the front and back plates, 40 adjacent the upper end of the cylinders.

The cylinders are closed by a head or plate 45 consisting of a casting 30 (Fig. 8) bolted to the block, and this plate may comprise a single section, and to prevent leakage the under side of the cylinder head has longitudinal tongues 31 which fit in corresponding grooves in the cylinder block at opposite sides of the cylinders, said grooves being indicated at 32 (see Fig. 7). The cylinder 50 head is recessed on the under side for the valves, said recesses being indicated at 33, and is cored as indicated at 34 and 35 for inlet and exhaust passages which open through inlet and exhaust ports 36 and 37 55 for the respective cylinders, the inlet passages communicating with fuel inlet pipes 38 and exhaust pipes 39 respectively. There is a pair of ports for each cylinder, and these ports are controlled by the slide valves 60 50. Each valve 50 consists of a flat plate of which there are four in all, each plate being provided with a port or opening 51 which is alternately registered in time with the inlet and exhaust ports 36 and 37 to charge 65 and exhaust the cylinder. The valves recip-

rocate in the recesses 33 on the under side of the cylinder head, said recesses opening through the head at the front and rear of the engine.

Each valve is operated by means of a crank 70 arm 52. As shown especially in Figs. 4 and 15 one crank arm for one of the valves at the rear of the engine is connected to the upper end of a shaft 53 the lower end of which has a crank arm 54 carrying a pin 55 75 which travels in a cam groove 56 in a cam 57 operated as hereinafter described. The other crank arm at the rear of the engine is connected to a sleeve 58 which encloses the shaft 53 and has a crank arm 59 with a pin 60 80 which travels in the groove 56 on the opposite side of the cam.

Each of the valves at the front of the engine is connected to the appropriate arm 52 by a rod 63 bolt 61 and spacing sleeve 62, and one of said arms is mounted at the upper end of a shaft 64 and the other at the upper end of a sleeve 65, the shaft 64 being connected to an arm 66 which carries a pin 67 traveling in a groove 68 in a cam 69, and the sleeve 65 being provided with an arm 70 having a pin 71 which also travels in said groove 68. These shafts and sleeves are supported by bearing brackets 72 and 73 bolted to the rear plate 10. The connection of the various valves with the respective arms 52 is made by means of slots 75 and pins 76 in said arms, and the throw of the valves can be varied by setting the pins at different places in the slots. 100

It will be seen that oscillation of the valve shafts and sleeves 53, 58, 64 and 65 will produce reciprocation of the valves timed according to the operation or the cycle, the cam grooves being correspondingly developed as shown in the diagram in Fig. 12. 105

The valve gearing comprises a gear 80 (Fig. 9) keyed on the crank shaft 16 within the cylinder block, and this gear meshes for two to one reduction with a large gear 81 fixed on a counter shaft 82 which carries a gear 83 meshing with a gear 84 which is loose on the cam shaft 16, and located outside of the cylinder casing. The gear 84 is bolted as indicated at 85 to the cams 57 and 59 which are also loose on the shaft 16, the bolts extending through slots 90 in the cams so that the latter may be set for proper timing. As the crank shaft is rotated, the two to one gearing causes corresponding rotation of the cams the grooves of which by the connections described operate the valve shaft and sleeves the motion of which is communicated to the valves individually. The valves are packed by packing 93 set into 110 grooves 94 extending crosswise between the grooves 32 in the top of the cylinder block, said packing extending the full width of the valves and somewhat beyond, one packing 115 strip being located at each side of each cylinder. 120

inder and pressing upwardly against the valve to prevent leakage thereunder. The packing is preferably of the spring strip type, and may be renewed by lifting off the 5 cylinder head and valves.

An advantage of the special form of valve shown is the quick opening and closing in consequence of the relatively long arm crank movement, as well as the large area 10 uncovered at each operation, giving a very quick supply and exhaust.

The cylinder block may be cored as indicated at 100 to allow the circulation of cooling water supplied from any suitable source. 15 The details may be accommodated to various local conditions, according to the number of cylinders employed or other purposes, and no limitation is implied with respect thereto, within the scope of the following 20 claims.

Among the practical advantages resulting from the construction described, it may be stated that the construction provides a high speed compression with a slow speed 25 crank shaft. That is, because of the translation of movement from the oscillating piston and rocker to the crank shaft the piston travel considerably exceeds the crank throw, with corresponding increased compression at 30 a higher speed. Another is that the intake and exhaust gases pass through the same port in the slide valve, and thus the heated port has a tendency to more thoroughly vaporize the charge while the inrushing gases 35 at the same time keeps the slide valve cool and prevents warpage.

Also since the pistons do not have to act as a guide for the various angles of travel of the connecting rod and are fully balanced it 40 is unnecessary for them to fit with great snugness and so called piston slap is entirely eliminated.

Preferably the engine would be embodied in multiples of two cylinders, say four, 45 eight or twelve cylinders, having one connecting rod for each four cylinders. Thus in an eight cylinder engine four cams are used instead of two, traveling between the two cylinder blocks, with one connecting rod 50 on the outer end of each cylinder block. It is also possible, particularly with an increased number of cylinders, to use an overhead cam shaft and tappet valves to advantage, instead of the slide valves, the cylinder

block design giving a large available space 55 for such an arrangement. However, the valve gear illustrated gives a very quick action—fully as quick as tappet valves. Instead of taking motion from a slow acting eccentric the slide valves are operated by 60 cams and relatively long rocker arms with a quick throw, so that quick opening and closing are provided.

I claim:

1. In an engine, the combination with a 65 cylinder block having a pair of opposite segmental cylinders therein, pistons reciprocating in said cylinders respectively, a rocker to which bolt pistons are connected, a crank shaft operatively connected to the rocker, a 70 detachable cylinder head fitting flatly on the top of the block, having inlet and exhaust ports therein, and slide valves in said head controlling said ports.

2. In an engine, the combination set forth 75 in claim 1, the rocker having a counterbalance on the side of its center opposite the piston connection.

3. In an engine, the combination set forth 80 in claim 1, the crank shaft extending across the block below the pistons and the rocker including a rock shaft set in the block above the connection thereto of the pistons.

4. The combination set forth in claim 1, 85 the pistons comprising a pair of heads at opposite ends of a single segmental channeled casting, the base web of the channeled casting being fastened to the side of the rocker.

5. In an engine, the combination set forth 90 in claim 1, said valves reciprocating across the head in lines parallel to the axis of the crank shaft.

6. In an engine, the combination set forth 95 in claim 1, the block at the head end of the cylinders having a single substantially flat plane surface across both cylinders, and the cylinder head comprising a plate fitting against said surface.

7. In an engine, the combination set forth 100 in claim 6, the contacting surfaces of the block and head having packing grooves.

8. In an engine, the combination set forth 105 in claim 6, the block having grooves and packing in said grooves pressing against the valves.

In testimony whereof, I affix my signature.

GEORGE WAGENLANDER.
